(57) **CLAIM**

The ornamental design of an extrusion for use with a gate panel frame, as shown and described.

DESCRIPTION

FIG. 1 is a side elevational view of an extrusion for use with a gate panel frame.

FIG. 2 is a perspective view thereof.

FIG. 3 is a side elevational view of a second embodiment of the extrusion for use with a gate panel frame.

FIG. 4 is a perspective view thereof.

FIG. 5 is a side elevational view of a third embodiment of the extrusion for use with a gate panel frame; and,

FIG. 6 is a perspective view thereof.
